Augustus B. Stoughton.

ATTORNEY.

UNITED STATES PATENT OFFICE.

HARRY E. SIMEK, OF PHILADELPHIA, PENNSYLVANIA.

YARN SEPARATOR FOR NECKTIE AND LIKE KNITTING MACHINES.

Application filed December 4, 1923. Serial No. 678,377.

To all whom it may concern:

Be it known that I, HARRY E. SIMEK, a citizen of the United States, residing at Philadelphia, in the county of Philadelphia 5 and State of Pennsylvania, have invented a new and useful Improvement in Yarn Separators for Necktie and like Knitting Machines, of which the following is a specification.

10 The principal objects of the present invention are, first, to prevent undue twist of the yarn below the knitting circle; to provide an efficient, durable and comparatively inexpensive yarn separator; to provide a 15 yarn separator in which the parts can be made of the most appropriate material and can be readily replaced and renewed; and to provide a yarn separator which cooperates with the ends of the yarn changer 20 fingers in such a way that impact between the two is avoided and durability thereby increased.

The invention will be claimed at the end hereof but will be first described in connection with parts of a necktie machine known 25 as a Brinton machine, and in connection with the embodiment of the invention chosen from other embodiments for the sake of illustration in the accompanying 30 drawings forming part hereof and in which—

Figure 1 is an elevational view with parts broken away and other parts in central section.

35 Fig. 2 is a top or plan view.

Fig. 3 is an end view of the yarn separator with parts of the machine broken away, and

Fig. 4 is an elevational view of one of the 40 plates detached.

In the drawings 1 is a generally circular open frame having opposed groups 2 and 3, of spaced yarn changer fingers depending toward the opening in the frame. So far 45 there has been described well known parts of a necktie knitting machine which happens to be of the Brinton type. 4 is an arbor detachably mounted on the frame 1 and arranged diametrically across the circular opening and between the ends 5 of the fingers of the respective groups. As shown notches 6 are provided in the top face of the frame 1 for the reception of the square ends 7 of the arbor 4. While 55 the arbor is shown as generally cylindrical

still it is provided with a flat 8. There is a series of heart-shaped plates 9 and washers 10 detachably strung in alternation on the arbor 4 and arranged with the lobes 11 of the heart-shaped plates between 60 and at the sides of the fingers and above the ends 5 of the latter when in elevated position and with the points 12 of the plates below the ends of the fingers when in depressed position. The plates may be 65 made of clock spring steel which is very durable, and they may be renewed by detaching the screws 13, taking off the arbor, detaching the screws 14, and taking the plates along with the washers over the end 70 of the arbor and then restringing the new plate or plates and washers on the arbor. The hole 15 in each plate is provided with a flat conforming with the flat on the arbor so that the plates are held firmly and against 75 turning movement.

It will be understood that in the operation of the machine the frame 1 is in rotation and the described yarn separator both by 80 reason of its construction and relative arrangement opposes undue twist of the yarn. Moreover the described yarn separator is durable and by reason of the position of the lobes 11 in respect to the ends 5 of the fingers, the parts are protected from wear 85 while at the same time they operate properly.

It will be obvious to those skilled in the art to which the invention relates that modifications may be made in details of construction and arrangement and in mere 90 matters of form without departing from the spirit of the invention which is not limited to such matters or otherwise than as the prior art and the appended claims may require.

95 I claim:

1. A yarn separator for knitting machines of the type set forth comprising a generally circular open frame having opposed groups of spaced yarn changer fingers depending towards said opening, an arbor detachably mounted on the frame and arranged diametrically across the circular opening and between the ends of the fingers of the respective groups, and a series of heart-shaped plates and washers detachably strung in alternation on said arbor and arranged with lobes of the heart-shaped plates between 100 and at the sides of the fingers and above the ends of the latter when in elevated position 105

and with the points of the plates below the ends of the fingers when in depressed position, substantially as described.

2. A yarn separator for knitting machines 5 of the type set forth comprising a generally circular open frame having opposed groups of spaced yarn changer fingers depending towards said opening, an arbor detachably mounted on the frame and arranged diamet- 10 rically across the circular opening and be- 15 tween the ends of the fingers of the respective groups, and a series of spaced heart-shaped plates mounted on said arbor and arranged with lobes of the heart-shaped plates be- tween and at the sides of the fingers and above the ends of the latter when in elevated position and with the points of the plates below the ends of the fingers when in de- 20 pressed position, substantially as described.

20 3. In a yarn separator the combination of an arbor having a flat surface, a series of

heart-shaped plates each having an opening provided with a flat surface and conforming to the arbor, a series of washers strung in alternation with the plates on said arbor, and means for detachably connecting the arbor and the other elements. 25

4. A yarn separator comprising a hollow frame facially notched, an arbor having an end conforming to said notch to oppose ro- 30 tation of the arbor in respect to the frame, means for connecting the end of the arbor and frame, a series of heart-shaped plates strung on the arbor and provided with open- 35 ings having straight portions conforming with a flat portion provided on the arbor to prevent rotation of the plates in respect to the arbor, and a series of washers strung on the arbor in alternation with the plates to space the latter.

HARRY E. SIMEK.
